JUAN KLEIN AND FEDERICO KLEIN, OF BUENOS AIRES, ARGENTINA.

IGNITION SYSTEM FOR MULTICYLINDER INTERNAL-COMBUSTION ENGINES, AND PARTICULARLY FOR AUTOMOBILE ENGINES.

Application filed June 27, 1923. Serial No. 648,078.

To all whom it may concern:

Be it known that we, JUAN KLEIN and FEDERICO KLEIN, citizens of the Republic of Germany, residing at Buenos Aires, Argentine Republic, have invented certain new and useful Improvements in Ignition Systems for Multicylinder Internal-Combustion Engines, and Particularly for Automobile Engines, of which the following is a specification.

Ignition systems are frequently employed, especially in light automobiles, wherein the primary current generated by a low-tension magneto (of a tension of about 6 to 8 volts) is brought to the primary windings of a number of ignition coils, corresponding to the number of cylinders of the engine. While the engine is running, one induction coil after another is brought into the low-tension magneto circuit during a short period of time, while the secondary terminal of the induction coil, which is directly connected with the spark plug, gives off an impulse of current at a tension of about 10,000 volts, causing a spark to jump the gap of the spark plug in the corresponding cylinder, to ignite the explosive gas mixture in the latter.

With the aforementioned and well known arrangement, as many induction coils are required as there are cylinders to the engine, which not only involves the multiplied cost of the induction coils, but also has the serious drawback that in case one of the coils becomes damaged or moist, or gets out of adjustment, the corresponding cylinder is likely to cease functioning.

The object of the present invention is the use of one single induction coil for all of the cylinders of the engine, thus making the engine more reliable and less contingent upon circumstances. Apart from the exchange of the usual low tension timer for the new timing device, no modification or alteration whatsoever is required in the motor itself, for which reason the present invention is particularly adapted for "Ford" automobiles, which are run on the above described system.

In the drawings attached hereto, the invention has been illustratively represented for its application to the engine of a "Ford" car.

Fig. 1 shows a partial section of the new timing device, according to the invention;

Fig. 2 is an interior view of the timing device, seen from its under side;

Figs. 3 and 4 represent the rotary timer member as seen from its under and upper faces, respectively;

Fig. 5 is a wiring diagram of the ignition system.

With reference to Figs. 1 and 2, the new timer consists of a case *a* of cylindrical shape, cast of a dielectric insulating substance. This case includes a radially-projecting portion *b*, having a cylindrical hub *c*, of which half protrudes from the portion *b*, said hub being provided for the purpose of mounting the actuating end of the ignition timing lever. In a central bore in the top of case *a*, beneath an insulating knob *d*, a contact pin *f* is mounted, pressed downward by a spring *e*, which is conductively connected with the terminal *g* on the projecting portion *b* of case *a*. The case is centrally provided with a wide bore which increases at its lower portion to a larger diameter and forms at the middle of its depth an annular shoulder or step, and within and flush with the surface of this step four radially disposed contacts are embedded. These contacts are indicated in the drawing by the characters *h*₁, *h*₂, *h*₃, and *h*₄, respectively, and are connected with the respective high tension terminals *j*₁, *j*₂, *j*₃, and *j*₄, from which leads run to the spark plugs in the cylinders.

The rim of the case has a rectangular incision with beveled edges for receiving and holding a small plate *k* with a dovetailed profile; this plate carries a contact spring *l* resiliently projecting into the case in a substantially radial direction, but slightly tilted upward. Spring *l* is fastened to plate *k* by means of terminal *m*, with which it is conductively connected.

Within case *a* rotates the concentric timing member *n*, constituted by a disc made of dielectric material, which carries on its upper face a central hub *o*, closed at its end. This hub is hollow, being provided within with a bronze bushing *o'* for receiving the end of the cam shaft *p*, on which it is properly adjusted by means of a groove and key.

Conductively connected with bushing *o'*, the lower face of the timer member *n* carries a number of radial arms equal to the number of cylinders in the engine; there being, in the construction illustrated, four radial arms *q*₁, *q*₂, *q*₃, *q*₄. (See Fig. 3).

Contact spring l pressing against the lower face of timer member n comes, upon rotation of the latter on the cam shaft, successively in contact with these arms.

- 5 $\mathfrak{b}$ On the upper face of timing member n , the insulating hub o carries a metal cap r with a central recess r' . A metal strip s' leads from metal cap r to a small bronze tube s , embedded near the periphery of 10 timer n . Within this tube s a carbon rod t is pressed upward by means of a small spiral spring t' . Upon rotation of timing member n , the carbon rod, resiliently bearing upon the surface above, makes successive contact with the electrodes h_1, h_2, h_3, h_4 .

The working of the ignition device of the present invention will be clearly seen by the wiring diagram of Fig. 5. The contact arms q_1, q_2, q_3, q_4 are connected, by 20 means of the bronze bushing o' of the timing member n , to the cam shaft p , and thus are grounded to the car frame. I is an induction coil of known construction, having its primary inlet terminal P connected 25 to the low-tension magneto terminal M , while its primary outlet terminal T is connected to the contact spring l by means of terminal m . The secondary terminal S of the induction coil is connected to the contact pin f by means of the terminal g . At 30 each half revolution of the crank shaft, the cam shaft moves through a quarter revolution, and at each quarter revolution one of the contact arms q_1, q_2, q_3, q_4 touches the 35 spring l , thus closing the low-tension circuit from terminal M , through induction coil I by electrodes P and T through terminal m , spring l and contact arm q . The 40 high tension current induced in the secondary winding of the induction coil, passes from terminal S to the central contact pin f in the timing case, through terminal g . Contact pin f presses against the recess r' of the metal cap r , and the current passes 45 through the metal strip s' to the bronze tube s and thence through carbon rod t , successively to contacts h_1, h_2, h_3, h_4 , over which the carbon rod is brushing during rotation of the timer member n . Each time the 50 spring l connects the low tension current traveling through the induction coil I , to the ground, through one of the contact arms q_1, q_2, q_3, q_4 , the high tension current gen-

erated in the secondary winding is led to one of the corresponding contacts h_1, h_2, h_3, h_4 , through terminal g , contact pin f , cap r and carbon rod t . Inasmuch as from the terminals j_1, j_2, j_3, j_4 , connected with the high tension terminals, leads run to the spark plugs of the corresponding cylinders 60 of the motor, 1, 2, 3, 4, an explosion occurs at each contact.

The lever u at the outside of the timing case may be connected with the lever by which the spark may be advanced or retarded, through rotation of timing case a .

According to whether the automobile is fitted with right hand or left hand steering gear, the spark lever is connected either with lever u or hub c of the timing case.

We claim as our invention:—

A timer for multi-cylinder engines, adapted to be mounted on the cam shaft of the engine and comprising a disc fixed to said shaft to constantly rotate therewith and having an upstanding hub; a case enclosing the disc and having a stepped bore providing a central annular shoulder which confronts one face of the disc, said disc being disposed in the outer portion of the bore, and its hub in the inner portion thereof; a set of contacts, one for each cylinder, embedded in the surface of said shoulder and connected to transmit high-tension current to the spark plugs; a metal member on the top of said hub; a metal contact pin mounted in said case in engagement with said member and connected with the source of high-tension current; a carbon brush mounted in the confronting face of the disc for successive engagement with the contacts, said brush being electrically connected with said metal member; a contact spring within the case connected with the low-tension current supply; and a plurality of radially-disposed contact arms, one for each engine cylinder, embedded in the other face of the disc for successive engagement by said spring to close the low-tension circuit, said arms being electrically connected at their inner ends with said shaft to ground the low-tension current.

In testimony whereof we affix our signatures.

JUAN KLEIN.
FEDERICO KLEIN.
